HATCH PLUG

Victor E. West, Chicago, Ill., assignor to Standard Railway Equipment Manufacturing Company, a corporation of Delaware

Application February 2, 1940, Serial No. 316,910

15 Claims. (Cl. 105—377)

This invention relates to hatch plugs, particularly insulated hatch plugs for the hatchways of railway car roofs. It has for its principal objects to devise a strong and durable plug that will be light, inexpensive and easy to maintain in working order, that will have its insulating material adequately protected against moisture, dirt and other foreign matter and which will be free from warping or shrinking out of shape. The invention consists in the hatch plug and in the construction, combinations and arrangements of parts hereinafter described and claimed.

In the accompanying drawings, which form part of this specification and wherein like symbols refer to like parts wherever they occur,

Fig. 1 is a plan view of a hatch plug embodying my invention.

Fig. 2 is a vertical section on the line 2—2 in Fig. 1.

Figs. 3 and 4 are enlarged vertical fragmentary sections on the lines 3—3 and 4—4, respectively, in Fig. 1.

Fig. 5 is an enlarged transverse section through the compressible sealing pad for said plug.

Fig. 6 is a fragmentary inner face view of the side frame of the plug, showing the margins of the sealing pad bent over the edges of said frame and secured inside thereof by lacing; and

Figs. 7, 8 and 9 are fragmentary sections, similar to Fig. 4, showing three modifications of the invention.

The plug illustrated in Figs. 1 to 6, inclusive, in the accompanying drawings, comprises an inverted pyramidal metal side frame A, metal closure plates B and C for the upper and lower ends, respectively, of said frame, suitable heat insulating material D in said frame between said closure plates, a compressible sealing pad E surrounding said frame with its longitudinal portions clamped between said closure plates and said frame and secured inside of the latter, and vertical through bolts F for securing said closure plates. As shown in the drawings the side frame A has rounded upper and lower edges 1 and 2, respectively, around which the longitudinal margins of the pad E are bent; and the top and bottom closure plates B and C have rounded marginal portions 3 and 4, respectively, similar to the rounded edges of said frame.

The sealing pad preferably comprises a tubular container made up of inner and outer strips 5 and 6 of textile fabric or other suitable material and a filling 7 of loose insulating material. The securing means for the corresponding marginal edges of the strips 5 and 6 preferably com-

prise hollow rivets or eyelets 8. The padding has a relatively thick middle portion and thinner portions between said middle portion and the margins of the fabric container. These thinner portions of the pad are compressed between and conform to the rounded cooperating edges of the metal side frame and closure plates; the margins of said container are secured together by laces 9 that pass through the eyelets 8 in said margins and thus serve to hold the padding in place on the edge frame.

The heads 10 of the through bolts F are welded or otherwise non-rotatably secured, as at 11, to the bottom closure plate C and have nuts 12 on their upper ends that bear against the top closure plate B. The top closure plate B has panels 13 pressed therein that extend from one side of said plate to the opposite side thereof and the nuts 12 of the bolts F are located in these panels. The bottom closure plate C is likewise paneled, as at 14, from one side of the plate to the opposite side thereof and the heads 10 of said bolts are located in these panels.

The hereinbefore described plug has several important advantages. It is light and relatively inexpensive, it has its insulating material protected against moisture and dirt and other foreign matter, it is strong and rigid and will not warp or shrink and lose its original shape, and the padding may be replaced when worn or damaged without replacing the other more permanent parts of the plug.

In the modified construction shown in Fig. 7, the metal side or edge frame A of the plug is provided substantially midway of its top and bottom edges with an inwardly extending stiffening and strengthening flange 15 whose inner marginal portion is slit and bent to provide upstanding tabs 16 and depending tabs 17 along the inner edge of said flange. Upper and lower wooden nailing strips 18 and 19 are disposed above and below the stiffening flange 15 between the inner edge tabs thereof and the side frame and are held in place by nails 20 that pass through said tabs and are driven into said filler strips. In this construction, the through bolts F extend through vertical holes provided therefor in the filler strips 18 and 19 and in the flange 15 of the edge frame; and the marginal edges of the padding are secured flatwise to the respective nailing strips by nails 21.

In the modification shown in Fig. 8, a single wooden nailing strip 22 is secured flatwise to the inner face of the edge frame A by means of horizontal bolts 23 having flat heads counter-

sunk in horizontal openings provided therefor in said frame and having their inner end portions threaded to receive nuts 24 that bear against the inner faces of said nailing strip.

The modification illustrated in Fig. 9 is similar to that shown in Fig. 7, except that a separate series of securing bolts F' is provided for each closure plate. In this construction, all of the bolts extend through the upper and lower nailing strips 18 and 19 and through the metal stiffening and strengthening flange 15 interposed therebetween. The bolts of one series are arranged with their heads 10a up and seated in countersinks provided therefor in the top of the upper nailing strip 18, while the lower ends of these 15 bolts extend through the bottom closure plate C and have nuts 12a threaded thereon that bear against the underside of said plate. The bolts of the other series are arranged with their heads down and seated in countersinks provided therefor in the bottom of the lower filler strip 19, while their opposite ends extend through the top closure plate B and have nuts threaded thereon that bear against the upper face of said plate. By this arrangement, each closure plate is secured by bolts that are independent of the securing bolts for the other closure plate; and an insulating space is provided between the securing bolts for one closure plate and the other closure plate, thereby preventing the transfer of heat by conduction through said bolts.

What I claim is:

1. A hatch plug comprising a frame and padding around the sides thereof, the upper and lower portions of said padding being bent around the top and bottom margins of said frame into the interior thereof, top and bottom covers for said frame, means for removably securing said covers in place, and means inside of said frame for holding said portions of said padding on said frame, said holding means being entirely independent of said covers and said cover-securing means.

2. A hatch plug comprising a hollow metal frame with curled top and bottom margins and compressible padding around the sides thereof, the upper and lower portions of said padding being bent around the curled top and bottom margins of the frame and provided with eyelets, and laces cooperating with said eyelets to hold said padding in place.

3. A hatch plug comprising a hollow metal frame with rounded top and bottom margins and padding around the sides thereof, said padding comprising a tubular container and a filling of insulating material in said container, the upper and lower portions of said container being bent around the rounded top and bottom margins of said frame and provided with eyelets, and laces cooperating with said eyelets to hold said padding in place.

4. A hatch plug comprising an inverted pyramidal hollow metal frame with rounded top and bottom margins and compressible padding around the sides thereof, said padding comprising a tubular container made of textile fabric and a filling of loose insulating material in said container, the upper and lower portions of said container being bent around the rounded top and bottom margins of said frame and provided with eyelets, and laces cooperating with said eyelets to hold said padding in place.

5. A hatch plug comprising an inverted pyramidal hollow metal frame with rounded top and bottom margins and compressible padding

around the sides thereof, said padding comprising a tubular container made of textile fabric and a filling of loose insulating material in said container, the upper and lower portions of said container being bent around the rounded top and bottom margins of said frame and provided with eyelets, laces cooperating with said eyelets to hold said padding in place, metal top and bottom closure plates for said frame having curved margins, and means for securing said plates to said frame with their curved margins bearing against said bent upper and lower portions of said container opposite the rounded top and bottom edges respectively of said frame.

6. A hatch plug comprising a metal side frame, a nailing strip fixedly mounted inside of said side frame, and a padding covering the outer face of said frame with its upper and lower margins bent inwardly around the top and bottom edges of said frame and secured to said nailing strip.

7. A hatch plug comprising a metal side frame, nailing strips fixedly mounted inside of said side frame, a padding covering the outer face of said frame with its upper and lower margins bent inwardly around the top and bottom edges of said frame and secured to said nailing strips, insulating material in said frame, metal top and bottom closure plates for said frame, and means for securing said closure plates.

8. A hatch plug comprising a metal side frame, nailing strips fixedly mounted inside of said frame, a padding covering the outer face of said frame with its upper and lower margins bent inwardly around the top and bottom edges of said frame and secured to said nailing strips, insulating material in said frame, metal top and bottom closure plates for said frame, and means for securing said closure plates to said frame with their margins bearing against said inwardly bent margins of said padding opposite the top and bottom edges respectively of said frame.

9. A hatch plug comprising a metal edge frame with an inwardly extending flange intermediate between the top and bottom of said frame, nailing strips located above and below said flange and sustained thereby, and a padding covering the outer face of said frame with its upper and lower margins turned inwardly over the top and bottom edges thereof and secured to the respective upper and lower nailing strips.

10. A hatch plug comprising a metal edge frame with an inwardly extending flange intermediate between the top and bottom of said frame, nailing strips located above and below said flange and sustained thereby, and a padding covering the outer face of said frame with its upper and lower margins turned inwardly over the top and bottom edges thereof and secured to the respective upper and lower nailing strips, said inwardly extending flange of said frame having portions bent upwardly alongside of the inner margin of the upper nailing strip and secured thereto and portions bent downwardly alongside of the inner margin of the lower nailing strip and secured thereto.

11. A hatch plug comprising a metal edge frame with an inwardly extending flange intermediate between the top and bottom of said frame, nailing strips located above and below said flange and sustained thereby, a padding covering the outer face of said frame with its upper and lower margins turned inwardly over the top and bottom edges thereof and secured to the respective upper and lower nailing strips, said inwardly extending flange of said frame having portions bent upwardly alongside of the inner margin of the upper

nailing strip and secured thereto and portions bent downwardly alongside of the inner margin of the lower nailing strip and secured thereto, insulating material in said frame, metal top and bottom closure plates for said frame, and means for securing said cover plates.

12. A hatch plug comprising a metal edge frame with an inwardly extending flange intermediate between the top and bottom of said frame, nailing strips located above and below said flange and sustained thereby, a padding covering the outer face of said frame with its upper and lower margins turned inwardly over the top and bottom edges thereof and secured to the respective upper and lower nailing strips, said inwardly extending flange of said frame having portions bent upwardly alongside of the inner margin of the upper nailing strip and secured thereto and portions bent downwardly alongside of the inner margin of the lower nailing strip and secured thereto, insulating material in said frame, metal top and bottom closure plates for said frame, and means for securing said cover plates to said frame with their margins bearing against said inwardly bent margins of said padding opposite the top and bottom edges respectively of said frame.

13. A hatch plug comprising a metal edge frame with an inwardly extending flange intermediate between the top and bottom of said frame, nailing strips located above and below said flange and sustained thereby, and a padding covering the outer face of said frame with its upper and lower margins turned inwardly over the top and bottom edges thereof and secured to the respective upper and lower nailing strips, said inwardly extending flange of said frame having portions bent upwardly alongside of the inner margin of the upper nailing strip and secured thereto and portions bent downwardly alongside of the inner margin of the lower nailing strip and secured thereto, insulating material in said frame, metal

top and bottom closure plates for said frame, and means for securing said cover plates to said frame with their margins bearing against said inwardly bent margins of said padding opposite the top and bottom edges respectively of said frame, said securing means comprising bolts extending through said closure plates, said nailing strips and said flange of said frame.

14. A hatch plug comprising a metal frame, padding fastened to and extending around the outer sides of said frame with its longitudinal margins bent around the top and bottom edges thereof, fastening means inside of said frame and in operative relation to the longitudinal margins of said padding for keeping said padding around the sides of said frame, metal top and bottom closures for said frame, and means for detachably securing said closures to said frame, said padding fastening means being entirely independent of said closures and the closure securing means, whereby the closures may be removed without loosening the padding.

15. A hatch plug comprising a metal frame open at its top and bottom, padding extending around the outer sides of said frame with its longitudinal margins bent around the top and bottom edges thereof and terminating inside thereof, detachable top and bottom closure plates for said frame, means for fastening said plates to said frame with their margins bearing against said margins of said padding adjacent to the top and bottom edges, respectively, of said frame, and means located entirely inside of said frame between and independent of said cover plates for fastening said padding to said frame, whereby said padding remains attached to said frame with its longitudinal margins positively retained around the top and bottom edges, respectively, of said frame and inside thereof when said top and bottom cover plates are detached therefrom.
